UNITED STATES PATENT OFFICE.

JAMES W. HALL, OF ALBANY, NEW YORK.

DEVICE FOR LOCKING A SERIES OF DRAWERS OR DOORS.

SPECIFICATION forming part of Letters Patent No. 341,746, dated May 11, 1886.

Application filed January 27, 1886. Serial No. 189,942. (No model.)

To all whom it may concern:

Be it known that I, JAMES W. HALL, a citizen of the United States, residing at Albany, New York, have invented a certain Improved 5 Device for Locking a Series of Drawers or Doors, of which the following is a specification.

The object of this invention is to construct a simple, cheap, and effective automatic locking device for a series of drawers of a cabinet, 10 a series of doors in a book-case, or a series of doors or drawers in articles of furniture generally, the whole being operated by the movement of one of the drawers or doors, as fully described hereinafter, and the device being of 15 such a character that the drawers need not be reduced in size for the reception of the same or the construction of the case modified other than by the recessing or cutting away of parts of the partitions therein.

20 In the accompanying drawings, Figure 1 is a perspective view of a cabinet a portion of which has been removed to show my improved locking device. Fig. 2 is a rear view in section of a cabinet, showing the drawers locked. 25 Fig. 3 is a plan view of part of Fig. 2, with the top of the cabinet removed. Fig. 4 is a detached perspective view of the locking device. Fig. 5 is a front view of the cabinet, and Figs. 6, 7, 8, 9, and 10 are views of modifications of my invention.

30 Referring to Fig. 1 of the drawings, A represents the frame of the cabinet or desk, and B B' B² are vertical partitions separating the drawers D, which are supported by and are 35 adapted to slide on horizontal ways or guides C on the side of the frame and on the intermediate partitions in any usual manner.

I have shown in Figs. 1 and 2 a desk or cabinet with four sets of drawers; but for convenience 40 I will describe the locking device as acting on two sets of drawers only, as the device is merely duplicated on the others.

Pivoted to the rear end of the partition B are two plates, g g, carrying upright locking-bars G G' at each end, which will form by this 45 connection as motion is imparted to them a parallel-ruler movement. One of these drawers, D', I term the "operating-drawer," as it controls the locking of all the others, and it is itself provided with an ordinary lock, m. (Shown in Fig. 3.) In one side of each of the

drawers D is a vertical groove, d, into which the upright locking-bars G G' may be inserted to lock the drawers. The upper end of one of the locking-bars, G, is connected by a link, 55 b, to a plate, a, which is hinged to the side of the partition in such a position that it will be in the path of the operating-drawer D'. A spring, e, which connects the two bars G G', tends to withdraw the said bars from the 60 grooves in the sides of the drawers and to throw the plate a outward when freed from the control of the operating-drawer.

The operation of the locking device is as follows: Supposing the operating-drawer D' 65 to be in its drawn out position, it will, on being moved inward, press the plate a toward the partition B. This movement will be communicated to the upright locking-bars G G', to move them outward, and thereby to cause 70 them to enter the grooves d in the drawers D, thus locking the latter. When the operating-drawer D' is pulled out again, the plate a is released from the control of the drawer D', and the spiral spring e will draw the locking- 75 arms G G' together and out of the grooves d in the drawers D, thus unlocking the latter.

When a locking device is to be provided for more than two sets of drawers, I attach a connecting-rod, f, to the upper end of one of 80 the locking-bars G G', (preferably by the same pin which connects the link b to the arm G.) The other end of this connecting-rod f is attached to one of the bars G G' of another set of locking-bars at the opposite side of the desk, 85 all intermediate sets being connected at convenient points to this rod f.

Instead of mounting the lock m for the operating-drawer D' in the drawer itself, it may be mounted in some convenient part of the 90 frame of the desk or cabinet adjacent to said drawer, as illustrated in the modification, Fig. 6.

In the modification Fig. 7 the retracting-spring e is placed in a recess in the partition 95 and bears against the hinged plate a.

In the modification Fig. 8 I have illustrated the plate a as in itself a spring; but I prefer in all cases, where practicable, to use the separate spring e.

It will be understood that in applying my invention to drawers arranged in single sets,

instead of in pairs, as above described, only one of the locking-bars G G' will be necessary, as illustrated in the modification Fig. 9. In this modification, also, I have shown the locking-bar G as hung at the upper end to one arm of a lever, g', the other arm of which is connected by a link, h, to the hinged plate a.

These modifications tend to disclose the nature of my invention; but I do not confine myself to these constructions alone—as, for example, the locking device may be placed in front instead of in the rear of the partitions, the operating-drawer may be any drawer of the series, and one of the locking-bars G G' may be used horizontally to lock a series of doors, such as often found in libraries, &c., the bar being located either at the top or bottom of a series of doors, or at any suitable intermediate point.

20 In Fig. 10, for instance, I have shown the locking-bar G placed at the bottom of the doors and adapted to enter grooves on the underside of all the doors, except the operating-drawer D', which is locked by an ordinary lock. 25 The operation of the locking-bar G is substantially the same as described above for locking the drawers, except that the hinged plate a is acted upon by the bottom edge of the door D' instead of by the side of drawer D. 30 In some cases I prefer to place the locking-arms G G' horizontal instead of vertical, in order to engage with notches g in the underside of one set of drawers and in the top of another set, the underside of the operating-drawer pressing on the hinged plate a moving the arms G G' out in precisely the same manner as described above. It will be clearly seen that by this combination of plain straight locking bar or bars with the two pivoting- 35 plates to impart motion to the bar or bars to enter or withdraw from the grooves d in the doors or drawers a simple, efficient, and inexpensive locking device is provided.

I claim as my invention—

1. The combination of a series of doors or 45 drawers of a desk, case, or cabinet with a locking device consisting of a hinged plate, a, adapted to be acted on by one of the doors or drawers, a locking-bar and the pivoting-plates g g therefor connected to the said hinged plate 50 to impart a side movement to the said locking-bar to engage with the doors or drawers, substantially as set forth.

2. The combination of a series of doors or 55 drawers of a desk, case, or cabinet having grooves d therein with a locking device consisting of a hinged plate, a, locking-bar G, and the pivoting plates g g therefor, said hinged plate a being adapted to be acted upon by one of the doors or drawers, forcing the 60 bar G with a side movement into the grooves d in the doors or drawers, substantially as set forth.

3. The combination of a series of doors or 65 drawers of a desk, case, or cabinet having grooves d with a locking device consisting of a hinged plate, a, to be acted upon by one of the doors or drawers, a connecting-link, b, locking-bar G, entering the grooves d in the doors or drawers, and pivoting plates g g 70 therefor, substantially as set forth.

4. The combination of two series of 75 drawers or doors of a desk, case, or cabinet with a locking device between the same, consisting of two locking-bars, G G', and pivoted plates g g, to the opposite ends of which said bars are connected and by which a sidewise parallel motion is imparted to the bars to lock the drawers or doors, substantially as set forth.

In testimony whereof I have signed my name 80 to this specification in the presence of two subscribing witnesses.

JAMES W. HALL.
